PHOTOGRAPHIC COMPOSING DEVICE AND
METHOD

Murray Friedel, North Miami Beach, Fla., assignor to
Visual Graphics Corp., New York, N.Y., a corpora-
tion of New York

Filed Nov. 7, 1960, Ser. No. 67,659
12 Claims. (Cl. 95—4.5)

This invention relates to photographic composing de-
vices and particularly apparatus for imprinting letters
upon a sensitized paper until a complete message is pro-
duced.

It is well known to project a series of letters upon a
piece of sensitized paper until a complete message has
been exposed on the emulsion. Thereafter, the sensitized
paper is removed from the projector and developed in
the well known photographic manner.

Accordingly it is an object of the present invention
to provide a rapid photographic composing device which
will overcome the defects of prior art apparatus.

Another object of the present invention is to provide
a photographic composing device in which the letters to
be imprinted can be watched before and during exposure
and developing stages.

A further object of the present invention is to provide
a photographic composing device in which the size and
shape of letters can be regulated optically without the
need for a large number of individual letter strips for pro-
jection purposes.

Still another object of the present invention is to pro-
vide a device in which the message being printed can be
observed as the operation continues thereby eliminating
the chances of mistakes.

Still another object of the present invention is to pro-
vide a photographic composing device which can be op-
erated in daylight or normal room illumination.

An object of the present invention is to provide a photo-
graphic composing device which is capable of producing a
wide variety of letter types, pictures and the like.

A feature of the present invention is its use of a de-
veloper filled tank or block within which the exposure is
made.

Another feature of the present invention is its use of a
window above the developing tank through which the op-
eration may be observed.

Still another feature of the present invention is its use
of a novel developing solution whereby successive letters
can be exposed and developed almost immediately as the
work progresses.

A feature of the present invention is its use of a series
of chemical retaining tanks or blocks above the sensitized
paper.

Still another feature of the present invention is its op-
tically adjustable projecting means whereby the size and
shape of the projected letters may be varied to achieve
interesting effects.

A further feature of the present invention is its use of
a cassette for daylight loading of the film into the photo-
graphic composing device.

Another feature of the present invention is its use of
a curved wall within the chemical receiving tanks whereby
air is eliminated from the paper receiving enclosure.

Still another feature of the present invention is its use
of additional developing, fixing and stop solutions as the
operation proceeds as the result of which uniformly ex-
cellent photographic imprinting may be achieved.

The invention consists of the construction, combina-
tion and arrangement of parts, as herein illustrated, de-
scribed and claimed.

In the accompanying drawings, forming a part hereof
is illustrated one form of embodiment of the invention

2

in which drawings similar reference characters designate
corresponding parts and in which:

FIGURE 1 is a somewhat isometric view of the film
exposing and developing section of the present invention.

FIGURE 2 is a diagrammatic isometric view of a com-
plete embodiment of a photographic composing device
made in accordance with the present invention.

FIGURE 3 is a view in side elevation partly broken
away of a complete embodiment of the present invention.

FIGURE 4 is an isometric view partly in section of a
chemical retaining and receiving block used in the present
invention drawn on an enlarged scale.

FIGURE 5 is a top plan view of the developing section
of the photographic composing device made in accordance
with the present invention.

FIGURE 6 is a sectional view taken on line 6—6 in
FIGURE 5, looking in the direction of the arrows.

FIGURE 7 is a fragmentary top plan view of the pro-
jection section of the photographic composing device.

FIGURE 8 is a detail view of the rotatable lens ar-
rangement for achieving special effects with the photo-
graphic composing device.

FIGURE 9 is a sectional view taken on line 9—9 in
FIGURE 3.

25 Referring to the drawings and particularly to FIG-
URES 1 and 2, 10 indicates a photographic composing
device consisting broadly of a developing section 11 and
a projection section 12. The developing section and pro-
jection section are interconnected by a light proof bellows
30 13.

The developing section 11, best shown in FIGURES
1—6, is enclosed within a housing 14 having an opening
15 in the top thereof around which is secured the bellows
13. Light coming through the bellows 13 from the pro-
jection section 12 as hereinafter more fully described, can
enter the interior of the housing 14 through the open-
ing 15.

Immediately below the opening 15 there is disposed a
40 transparent block 16 formed of Lucite, glass or the like,
and hereinafter referred to as the developing tank. The
developing tank 16 is carried upon a table 17 within the
housing 14. A second block 18 is disposed adjacent the
developing tank upon the table 17 and is hereinafter re-
ferred to as the stop tank. A third block 19 is carried
45 upon the table 17 adjacent the stop tank 18 and is hereinafter referred to as the fixing tank. The tanks 16, 18,
19, as best shown in FIGURE 4, rest upon a strip of
sensitized paper 20 preferably of the chloride emulsion
type which is advanced through the composing device as
it is operated. It will be observed from an examination
50 of FIGURE 4 that the tanks 16, 18, 19, are formed of
solid blocks of material which are recessed at the bottom
thereof, to form with the sensitized paper 20, a chemical
receiving cavity 21. The cavity 21 is in communication
55 with vertical channels 22, 23, which are provided in the
body of the tanks 16, 18, 19. Small pipes 24, 25, 26, lead
from the channels 22, 23, to the outside of the tanks 16,
18, 19, for the purpose of conducting developing, fixative,
60 and stop solutions into the respective tanks. In addition,
the tanks are provided with small openings 27, in the sides
thereof, which openings permit the chemicals within the
tanks to escape therefrom. The openings 27 constitute
overflow paths for surplus chemicals.

65 As shown in FIGURES 2 and 5, the tanks 16, 18 and
19, are held in close contact with the paper 20 by means
of spring-like arms 28. The arms 28 are secured to the
structure of the housing 14 and are provided with small
rubber tips 29 which bear against the top of the tanks
70 16, 18, 19. The bottom surfaces of the tanks 16, 18, 19,
which bear against the surface of the paper 20 are care-
fully polished so that the liquid within the cavity 21 of

the tanks 16, 18, 19, remains therein despite that fact that the paper 20 is slid beneath the said tank.

Motion of the paper 20 through the machine is imparted by means of spaced transport arms 30 which are carried by an elongated bracket 31. During the exposing and developing operation of the device the transport arms 30 are in an elevated position as shown in FIGURE 6. However, when it is desired to move the sensitized paper 20, a small lever 32 on the front of the housing 14 is depressed. The lever 32 is connected to the bracket 31 and rotates it until the transport arms 30 come into contact with the sensitized paper 20. The transport arms 30 are provided with rubber pads 33 which make a firm frictional contact with the paper. Thereafter, a transport lever 34 on the front of the housing 14 is rotated in a counter-clockwise direction. The transport lever 34 is attached to a small spur gear 35 which is secured to the end of a shaft 36. The spur gear is also in mesh with a gear rack 37 secured to the bottom of the housing 14. The end of the shaft 36 opposite the spur gear 35 is journaled within the bracket 31. As the transport lever 34 is rotated, therefore, it causes the spur gear 35 to travel along the gear rack 37 thereby moving the shaft 36 and the bracket 31 laterally within the housing 14 and between supporting rollers 31a. The lateral motion of the bracket 31 causes the transport arms 30 to move therewith and advance the paper 20 through the machine. It will be understood that the paper 20 is resting upon the table 17 and that the transport arms 30 hold the paper 20 against the table 17 in advancing it through the machine. When the lever 32 is released the transport arms 30 will spring away from the paper 20 and the transport lever 34 may be rotated in a clockwise direction to return the arms 30 to their original position. In this manner, the sensitized paper 20 may be advanced through the machine an amount sufficient to carry it from tank to tank and also sufficient to space successive letters from each other the desired distance.

A viewing station generally indicated at 38 in FIGURES 1 and 3 is carried by the housing 14 above and in front of the developing tank 16. The viewing station 38 consists of a hood 39, a glass plate 40 made of a suitable tinted glass such as is used for safe lights, and an enlarging lens 41 to clearly see the letter or other legend which is being projected upon the sensitized paper 20 below the developing tank 16. It will be understood that the developing tank 16 when filled with developing fluid 42 appears optically as a solid transparent block through which the sensitized paper 20 and any light projected thereon may be viewed. Because of the safe light nature of the glass plate 40, light entering the viewing station 38 through the said plate 40 does not affect the sensitized paper 20. A small safe light bulb 43 is provided within the viewing station 38 adjacent the developing tank 16 for the purpose of observing the developing operation. The bulb 43 is connected to a source of potential through a switch 44 which enables the operator to turn the bulb on as desired. The container of developing solution indicated at 45 is mounted upon the housing 14 and connected to the pipe 24 of the developing tank by means of a small conduit 46. A second container 47 in which there is placed a stop solution is carried upon the housing 14 and is connected to the pipe 25 on the stop tank 18 by means of a small conduit 48. A third container 49 is provided on the housing 14 to hold a fixing solution led into the pipe 25 of the fixing tank 19 by a small conduit 50. A cycling lever 51 which projects from the front of the housing 14 is connected by means of a rod 52 to valves 53 beneath the containers 45, 47 and 49. When the cycling lever 51 is pressed it opens the valves 53 and permits a small amount of the fluids within the containers to pass through the conduits and into the tanks 16, 18 and 19. The fresh chemicals are added to the chemicals already in the tanks and cause the tanks to overflow through the openings 27 from which they flow down

through the housing 14 and are led into a small reservoir 54. The reservoir 54 is carried within the housing 14 and may be emptied as desired. In this manner, the developing chemicals within the tanks are always fresh and the developed legend or message is of uniform excellence.

The sensitized paper 20 of the photo-composing device is carried within a cassette 55, best shown in FIGS. 1 and 2. The cassette 55 consists of a small box within which the roll of film is carried. The box of the cassette 55 is provided with a slot 57 in the bottom thereof through which the paper 20 can be drawn. The slot 57 is provided with a light trap in the well kept manner. With the cassette 55 abutting the housing 14, the paper 20 can be drawn from the cassette and advanced through the machine without danger of exposing the film in the cassette to ambient light. It will be observed from an examination of FIGURE 5 that the spring arms 23 are pivotally mounted so that the tanks 16, 18, 19, can be removed from the table 17 to permit the paper 20 to be stretched thereacross. Thereafter, the tanks can be returned to their proper location and the arms 28 swung back over them in order to hold them tightly against the paper. The hood 39 and its supporting removable cover 56 protects the paper 20 from room light until it leaves the developing tanks 16, 18, 19.

The projector section 12 of the photographic composing device consists of a housing 58 within which there is carried a lamp 52 and the well known projector lens elements (not shown). A film guide 59 is provided on the front of the housing 58 and is adapted to receive a strip of film 60. The film 60 has a plurality of letters or symbols thereon which can be moved into the opening 61 in the film guide 59 so that light passing through the film guide 59 from the projector housing 58 will pass through the film. The film 60 may be moved from side to side on reels 62, 63, so that the desired letters can be brought into register with the openings 61 for projection purposes.

The film guide 59 is also provided with a rotatable amount 64 within which there is supported a lens 65, see FIGURE 8. The lens 65 is of a configuration that when it is in a horizontal position the letters projected therethrough will be vertically compressed and when it is swung into a vertical position the letters will be horizontally compressed. In addition, by disposing the lens 65 at various angles a slant lettering effect may be achieved. In this manner, a wide variety of lettering styles may be produced without changing the film strip 60.

The light coming through the lens 65 is directed at a mirror 66 which is angularly disposed within an enclosure 67 secured to the top of the bellows 13. An opening 68 is provided in the enclosure 67 to permit the light to enter the enclosure and reach the mirror. The mirror 66 directs the light from the projector downwardly through the bellows 13 and upon the sensitized paper 20 beneath the developing tank 16. A small lens 69 is carried within the top of the bellows 13 to assist in the projection of the image upon the sensitized paper 20.

A suitable safe light shield 69a is swingably carried within the housing 58 in front of the projector lamp and remains in front of the said lamp at all times except when the exposure is being made. In this manner, the light can project the letters upon the sensitized paper where it can be observed by the operator 70 until the latter is exactly located for the desired message imprinting. Thereafter, the safe light shield 69a is swung away and the projection light permitted to pass through the film for exposure purposes.

It will be observed from FIGURES 3 and 9, the projection section 12 is mounted upon a vertical and horizontal support 71, 72, whereby it may be moved vertically and horizontally with respect to the developing section 11. As a result of this adjustability, it is possible to increase or decrease the size of the projected letters, optically,

merely by increasing or decreasing the length of the path of the light from the projection section 12 to the sensitized paper 20 in the developing section 11. As shown in FIGURE 9 the vertical support 72 is provided with a scale 73 adjacent the edge thereof. Pointers 74 carried on the projection section bracket 80 overlie the scale 73 and permit the vertical adjustment of the projection section with accuracy. A flexible rule 90 on the projection section is provided for accurate horizontal setting. The projection section 12 is moved back and forth upon the horizontal support 72 by means of a crank 75 which is secured to the end of a shaft 76 on which sprocket wheels 77 are mounted. The sprocket wheels drive a chain 78 which passes over pulleys (not shown) on the horizontal support and which is also secured to the projection section to move it back and forth upon the horizontal support 72. A flexible tape 79 is attached at one end to the bracket 80 which carries the horizontal support 72. The vertical tape 79 is passed over a pulley 81 which is provided with a tensioning clutch (not shown) to hold the projection section 12 on the vertical support 71 in any set position. It will be understood that as the projection section is raised and lowered, the bellows 13 will be elongated or compressed as the enclosure 67 is raised or lowered.

A preferred developing solution for use in conjunction with the present photographic device is as follows:

Part #1:

Water, 125 degrees, 24 ounces
Metol, 45 grains
Sodium sulphite dessicated, 1 oz., 246 grains
Hydroquinone, 165 grains
Sodium carbonate monohydrated, 1 oz., 245 grains
Potassium bromide, 22½ grains
Cold water to make 32 ounces, then dilute 1 to 2 before using.

Part #2:

32 oz. water (warm)
½ oz. potassium bromide

Part #3:

32 oz. warm water
Anti-Fog #1, 30 grains

Part #4:

32 oz. water
Sodium sulphate 1 oz.

All chemicals are mixed in the order as follows: 8 oz. Part #1, add 2 oz. Part #2, 4 oz. Part #3, and 6 oz. Part #4.

Solution Part #1, is the basic developing formula and is an extreme contrast developer of high speed for chloride emulsion papers. Solution #2 is added to decelerate the action of the metol hydroquinone to get a visible image time within the developing tank within five seconds after the exposure. Solution #3 is used to eliminate side reactions of the chemicals which create irregular grayish streaks on the emulsion of the paper. Solution #4 eliminates pink stains which would normally appear from continued exposure of the emulsion to oxygen.

A suitable stop solution for use in the present invention consists of 4 ounces of acetic acid 28% to which is added cold water to make 32 ounces.

A suitable fixative solution for use in conjunction with the present invention consists of ammonium thiosulphate 1 lb., potassium metabisulphite 2 ounces, and cold water to make 1 gallon.

Metol referred to hereinabove is also sold by different companies under the trade-names, Rhodol, Elon, Genol, Photol, etc., and consists of monomethyl para-aminophenol sulphate; parahydroxy-monomethylaniline sulphate; 1 hydroxy-4-methylaminobenzene sulphate. Anti-Fog #1, referred to hereinabove is the trade-name for, Benzitriazol, a developer improver.

With the developer, stop and fixative solution in the proper containers and the sensitized paper threaded

beneath the tanks 16, 18, 19, the letter displaying film 60 in place, the photographic composing device is ready for operation. The proper letter is brought into register with the opening 61 in the film guide and the projector light 82 turned on. The light 82 is controlled by means of switch 84. The letter to be photographically printed will then show up on the paper 20 within the viewing station 38. Since the safe light shield 69 is in place in front of the projector bulb 82 there will be no exposure at this junction. The projection section 12 can then be adjusted vertically and horizontally to give the letter the proper height. In addition, the lens 65 on the front of the film guide 59 can be rotated to alter the shape of the letter in the manner hereinabove described.

As the developing fluid flows into the cavity 21 and by reason of the curved wall 86, in the top of the cavity, the said cavity fills and forces any air therein upwardly and out of the vent holes or openings 27. In this manner no air can be entrapped within the cavity 21 to the detriment of the developing operation. With the projected letter in proper alignment, orientation and size, the operator next presses the cycling lever 51 which serves to release a small supply of chemicals to the tanks 16, 18, 19. A timer switch 85 is then thrown which swings the safe light shield 69 from in front of the projector bulb and also keeps it in the exposing position for the given or desired interval of time. The time interval is governed by the timer 83 in the housing 11. At the end of the exposure the safe light shield 69 swings back into place following which the development of the letter can be observed through the viewing station 38. The small light 43 may be turned on by means of the switch 44 to watch the developing action. As soon as the letter is developed the transport arm lever 32 is depressed and the transport lever 34 rotated in order to move the letter out of the way for the next exposure. A suitable next letter is selected on the film 60 and the operation repeated. It will be observed that as the letters move out of the developing tank 16 they slide beneath and into the stop tank and then into the fixing tank 19. After the sensitized paper leaves the fixing tank 19, the last remaining bit of chemical is wiped clear by means of a squeegee 86, see FIGURE 5, and is practically ready for use.

The specific mechanism for moving the safe-light shield 69 has been shown as a solenoid 87, a gear 88 and a gear rack 89, however, it will be apparent that other well known means may be used for this purpose.

From the foregoing it will be seen that there has been provided a photographic composing device which is capable of a wide variety of printing operations all of which may be carried out in ordinary room illumination without danger of accidentally exposing the paper. In addition, the apparatus permits the operator to watch the formation of the letters and to adjust and arrange them as the printing is carried on. Each letter is developed under the viewing station so that the operator at all times can be aware of the nature and spacing of the letters produced. There has also been provided a novel developing technique whereby the projected letters are recorded on the sensitized paper while the paper is actually within the developing solution.

Having thus fully described the invention what is claimed as new and desired to be secured by Letters Patent of the United States, is:

1. A photographic composing device comprising a projection section, a developing section, and a light proof hollow member providing a light path from the projection section to the developing section, a light sensitive member carried within the developing section beneath the hollow member, at least one transparent tank-like member overlying the light sensitive member, a source of developing fluid connected to the tank-like member to fill the said member and cover the light sensitive member beneath the tank-like member, and means to project an image upon the light sensitive member through the fluid

filled tank-like member whereby the image is photographically imprinted thereon.

2. A photographic composing device comprising a projection section, a developing section, and a light proof hollow member providing a light path from the projection section to the developing section, a table in the developing section, a light sensitive member carried within the developing section beneath the hollow member upon the table, at least one transparent tank-like member overlying the light sensitive member on top of the table, a fluid receiving cavity in the bottom of the tank-like member, a source of developing fluid connected to the tank-like member cavity to fill the said member and cover the light sensitive member beneath the tank-like member, and means to project an image upon the light sensitive member through the fluid filled tank-like member, whereby the image is photographically imprinted thereon.

3. A photographic composing device comprising a projection section, a developing section, and a light proof bellows member providing a light path from the projection section to the developing section, a light sensitive member carried within the developing section beneath the bellows, at least one transparent tank-like member overlying the light sensitive member, a source of developing fluid connected to the tank-like member to fill the said member and cover the light sensitive member beneath the tank-like member, means to project an image upon the light sensitive member through the fluid filled tank-like member, whereby the image is photographically imprinted thereon, and means to transport the light sensitive member through the developing section.

4. A photographic composing device comprising a projection section, a developing section, and a light proof hollow member providing a light path from the projection section to the developing section, a light sensitive member carried within the developing section beneath the hollow member, at least one transparent tank-like member overlying the light sensitive member, a source of developing fluid connected to the tank-like member to fill the said member and cover the light sensitive member beneath the tank-like member, a viewing station above the tank-like member comprising a hood and a window in said hood for observing the light sensitive member beneath the tank-like member, and means to project an image upon the light sensitive member through the fluid filled tank-like member, whereby the image is photographically imprinted thereon.

5. A photographic composing device comprising a projection section, a developing section, and a light proof bellows member providing a light path from the projection section to the developing section, a table in the developing section, a light sensitive member carried upon the table within the developing section beneath the bellows, a first transparent tank-like member disposed upon the light sensitive member on top of the table, a first fluid receiving cavity in the bottom of the first tank-like member, a source of developing fluid connected to the first cavity to fill the said cavity and cover the light sensitive member beneath the first tank-like member, a second tank-like member upon the table disposed upon the light sensitive member and adjacent the first tank-like member, a second fluid receiving cavity in the bottom of the second tank-like member, a source of stop solution connected to the second cavity to fill the cavity and cover the light sensitive member thereunder, a third tank-like member upon the table disposed upon the light sensitive member, and adjacent the second tank-like member, a third fluid receiving cavity in the bottom of the third tank-like member, a source of fixative solution connected to the third cavity to fill the third cavity and cover the light sensitive member thereunder, means to project an image from the projection section upon the light sensitive member through the fluid filled first tank-like member whereby the image is photographically imprinted thereon and means to transport the light sensitive member across the

table and through the fluid filled cavities of the first, second and third tank-like members.

6. A device according to claim 5 in which the developing fluid is an extreme contrast developer of high speed for chloride emulsion papers containing a decelerator to extend the developing time.

7. A device according to claim 5 in which the projection section is provided with a lens rotatably mounted thereon and an image film disposed between the lens and the remainder of the projection section whereby the projected image may be varied by the angular disposition of the lens.

8. A photographic composing device comprising a projection section, a developing section, and a light proof bellows member providing a light path from the projection section to the developing section, a table in the developing section, a light proof cover member above the table, a viewing station comprising a hood secured to the cover member, said cover member being provided with an opening beneath the hood and a safe-light transparent window in the hood for observing interior of the cover member, a light sensitive member carried upon the table within the developing section beneath the bellows and cover member, a first transparent tank-like member disposed upon the light sensitive member on top of the table and beneath the cover member, a first fluid receiving cavity in the bottom of the first tank-like member, a source of developing fluid connected to the first cavity to fill the said cavity and cover the light sensitive member beneath the first tank-like member, a second tank-like member upon the table disposed upon the light sensitive member and adjacent the first tank-like member, a second fluid receiving cavity in the bottom of the second tank-like member, a source of stop solution connected to the second cavity to fill the cavity and cover the light sensitive member thereunder, a third tank-like member upon the table disposed upon the light sensitive member, and adjacent the second tank-like member, a third fluid receiving cavity in the bottom of the third tank-like member, a source of fixative solution connected to the third cavity to fill the third cavity and cover the light sensitive member thereunder, means to project an image from the projection section upon the light sensitive member through the fluid filled first tank-like member whereby the image is photographically imprinted thereon and means to transport the light sensitive member across the table and through the fluid filled cavities of the first, second and third tank-like members.

9. A device according to claim 8 in which the tank-like member cavities are formed with a curved top wall to provide an area of minimum depth at the center of the cavity and curve upwardly to join vertical fluid receiving channels in the tank-like members.

10. A device according to claim 8 in which the tank-like members are held in fluid tight contact with the light sensitive member by springs carried within the developing section.

11. A photographic composing device comprising a projection section, a source of illumination in the projection section, a safe-light filter in front of the illumination source, means to shift the safe-light filter from its position in front of the illumination source to permit the unfiltered light to leave the projection section, a developing section, and a light proof bellows member providing a light path from the projection section to the developing section, a table in the developing section, a light sensitive member carried upon the table within the developing section beneath the bellows, a first transparent tank-like member disposed upon the light sensitive member on top of the table, a first fluid receiving cavity in the bottom of the first tank-like member, a source of developing fluid connected to the first cavity to fill the said cavity and cover the light sensitive member beneath the first tank-like member, a second tank-like member upon the table disposed upon the light sensitive member and adjacent the first tank-like member, a third tank-like member upon the table disposed upon the light sensitive member, and adjacent the second tank-like member, a third fluid receiving cavity in the bottom of the third tank-like member, a source of fixative solution connected to the third cavity to fill the third cavity and cover the light sensitive member thereunder, means to project an image from the projection section upon the light sensitive member through the fluid filled first tank-like member whereby the image is photographically imprinted thereon and means to transport the light sensitive member across the

the first tank-like member, a second fluid receiving cavity in the bottom of the second tank-like member, a source of stop solution connected to the second cavity to fill the cavity and cover the light sensitive member thereunder, a third tank-like member upon the table disposed upon the light sensitive member, and adjacent the second tank-like member, a third fluid receiving cavity in the bottom of the third tank-like member, a source of fixative solution connected to the third cavity to fill the third cavity and cover the light sensitive member thereunder, means to project an image through the safe-light filter upon the light sensitive member through the fluid filled tank, means to shift the safe-light filter from the source of illumination to project an image from the projection section upon the light sensitive member through the fluid filled first tank-like member whereby the image is photographically imprinted thereon and means to support the light sensitive member across the table and through the fluid filled cavities of the first, second and third tank-like members.

12. A photographic composing device comprising a projection section, a source of illumination in the projection section, a safe-light filter in front of the illumination source, means to shift the safe-light from its position in front of the illumination source to permit the unfiltered light to leave the projection section, a developing section, and a light proof bellows member providing a light path from the projection section to the developing section, a table in the developing section, a light proof cover member above the table, a viewing station comprising a hood secured to the cover member, said cover member being provided with an opening beneath the hood and a safe-light transparent window in the hood for observing the interior of the cover member, a light sensitive member carried upon the table within the developing section beneath the bellows and cover member, a first transparent tank-like member disposed upon the light sensitive member on top of the table and beneath the cover member, a

first fluid receiving cavity in the bottom of the first tank-like member, a source of developing fluid connected to the first cavity to fill the said cavity and cover the light sensitive member beneath the first tank-like member, a second tank-like member upon the table disposed upon the light sensitive member and adjacent the first tank-like member, a second fluid receiving cavity in the bottom of the second tank-like member, a source of stop solution connected to the second cavity to fill the cavity and cover the light sensitive member thereunder, a third tank-like member upon the table disposed upon the light sensitive member, and adjacent the second tank-like member, a third fluid receiving cavity in the bottom of the third tank-like member, a source of fixative solution connected to the third cavity to fill the third cavity and cover the light sensitive member thereunder, means to project an image through the safe-light filter upon the light sensitive member through the fluid filled tank, means to shift the safe-light filter from the source of illumination to project an image from the projection section upon the light sensitive member through the fluid filled first tank-like member whereby the image is photographically imprinted thereon and means to transport the light sensitive member across the table and through the fluid filled cavities of the first, second and third tank-like members.
